(57) **CLAIM**

The ornamental design for a bag, as shown and described.

DESCRIPTION

FIG. 1 is a front, right-side, top perspective view of the bag, showing the new design;

FIG. 2 is a rear, right-side, top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right-side elevational view thereof;

FIG. 8 is a left-side elevational view thereof;

FIG. 9 is a perspective view showing the adjustable strap portion disconnected from the bag; and,

FIG. 10 is a perspective view showing the adjustable strap portion disconnected from the bag.

The adjustable strap portion is shown individually in FIGS. 9 and 10 to show individual aspects of the overall design. The broken lines depict parts of the bag that form no part of the claimed design.

1 Claim, 10 Drawing Sheets
